Patented Oct. 26, 1920.

Application filed April 15, 1920. Serial No. 374,238. Term of patent 3½ years.

To all whom it may concern:

Be it known that I, WATSON S. SIDÉ-LIVERMORE, a citizen of the United States, and a resident of the city of New York, borough of Manhattan, county and State of New York, United States of America, have invented a new, original, and ornamental Design for an Image, of which the following is a specification, reference being had to the accompanying drawing, forming a part thereof, wherein—

Figure 1 represents a three-quarter front view, and

Fig. 2 represents a three-quarter back view of an image showing my new design.

My design consists of the representation of a juvenile female figure clothed in a one piece garment and arranged in a posture expressive of bashfulness.

The design is molded, cast, carved, stamped, or otherwise produced, from metal, wood, textile, paper, brass, horn, bone, or ivory.

What I claim and desire to secure by Letters Patent, is:

The ornamental design for an image substantially as shown and described.
